IRONING BOARD

Sheldon Jacobowitz, Brooklyn, N. Y.

Application December 1, 1949, Serial No. 130,383

9 Claims. (Cl. 219—40)

1

This invention relates to a structurally and functionally improved ironing board.

The present application is a continuation in part of my earlier application for United States Letters Patent filed on June 4, 1948 and identified under Serial Number 31,147 now Patent No. 2,527,363 of October 24, 1950.

It is an object of the invention to provide an ironing board capable of household or commercial use and by means of which the material being ironed will be properly moistened and conditioned so that extremely desirable finished results are obtained.

A further object is that of providing a structure which will include relatively few parts, each individually simple and rugged in design; such parts being capable of ready assemblage to furnish a unitary apparatus functioning over long periods of time with freedom from all difficulties.

With these and other objects in mind, reference is had to the attached sheet of drawings illustrating one practical embodiment of the invention and in which:

Fig. 1 is a perspective view of the ironing board with certain of the covering material removed therefrom;

Fig. 2 is a plan view of such board with certain of the parts broken away to disclose underlying construction;

Fig. 3 is a sectional side view taken along the lines 3—3 and in the direction of the arrows as indicated in Fig. 2;

Fig. 4 is a fragmentary perspective view showing the heater assembly and accessory structure which may form a part of the board; and

Fig. 5 is a somewhat diagrammatic representation of the wiring circuits which are preferably incorporated.

In these views the reference numeral 10 indicates the body of the board which is hollow and preferably formed of heat-resistant plastic reinforced by, for example, glass fiber. As shown, this board includes upper and lower surfaces maintained in spaced relationship by side walls. The upper surface is formed with suitable perforations 11 and may be provided with a layer of porous material 12 through which moisture will pass from the vents. Thus, in effect, an envelope structure is furnished, the end edge of which is open so that access may be had to the interior of the same. That end edge is normally closed by a sealing strip 14. A rib 13 extends lengthwise of the enclosure and terminates at a point short of the end of the same.

Within the space thus furnished, an electric heater is disposed. This conveniently includes any desired number of electrodes 15 mounted upon insulating supports 16. A switch 17 is provided. Leads and terminals 18 extend from one of the electrodes and the switch to be coupled to a source of electric power. A knob 19 is conveniently attached to the actuator of the switch which projects beyond the upper surface of the body 10 of the board and preferably in advance of the covering 12.

In this manner it is feasible for the operator to control the amount of heat which is generated by operating the actuator 19. In this connection it will be understood that according to a preferable wiring arrangement, the switch may be shifted from open position to a position at which one, or any desired number of the electrodes are energized. The body 10 will, of course, receive liquid which will be vaporized by the heat generated by the resistance to current passage through the liquid and will pass in the form of vapor through the perforations 11. While not essential, it is preferred that in order to maintain the electrodes in contact with the liquid, body 10 extends in a slightly inclined plane so that the end mounting the heater structure will be slightly lower than the opposite end of the board. To achieve this result, the legs associated with the latter may be properly proportioned or be adjusted. Only three electrodes have been shown. It is obvious that any desired number of these elements—arranged in spaced series—might be employed.

In order to fill the interior of the hollow body with water, an opening may be formed through its upper surface at a point adjacent its rear end. This opening may be normally closed by a cap 20 which, when removed, permits of the introduction of water. Likewise the lower surface of the body may be formed with an opening 21 normally closed by a plug 22 or otherwise so that undesired liquid may be drained from the interior of the board. It is apparent that strip 14, in addition to reenforcing the free edges of the body also permits of access to the interior of the latter upon such strip being dismounted. Normally, however, the latter will be in liquid sealing contact with the inner surfaces of the body.

Thus, among others, the several objects of the invention as afore described are achieved. Obviously numerous changes in construction and rearrangement of the parts might be resorted

to without departing from the spirit of the invention as defined by the claims.

I claim:

1. An ironing board comprising a hollow body, the top surface of said body being formed with perforations and an electric heater disposed within said body and solely adjacent one end thereof.

2. An ironing board comprising a hollow body, the top surface of said body being formed with 10 perforations, an electric heater disposed within said body and solely adjacent one end thereof and said body being inclined with respect to the horizontal and extending downwardly in the direction of said heater.

3. An ironing board comprising a hollow body, the top surface of said body being formed with 20 perforations, an electric heater disposed within said body and solely adjacent one end thereof and a rib extending lengthwise within said body between the top and lower surfaces thereof.

4. An ironing board comprising a hollow body, the top surface of said body being formed with 25 perforations, an electric heater disposed within said body and solely adjacent one end thereof and a rib extending lengthwise within said body and terminating at a point short of said heater.

5. An ironing board comprising a hollow body, the top surface of said body being formed with 30 perforations, an electric heater disposed within said body and solely adjacent one end thereof and said body being formed with filling and draining openings at points adjacent said heater.

6. An ironing board comprising a body in the 35 form of an envelope embracing spaced top and bottom surfaces and edge walls, said envelope being open at one end, an electric heater disposed within said envelope adjacent such open end and said top surface being formed with perforations.

7. An ironing board comprising a body in the 40 form of an envelope embracing spaced top and bottom surfaces and edge walls, said envelope being open at one end, an electric heater disposed within said envelope adjacent such open end and said top surface being formed with perforations, and said envelope being closed at the other end by a closure strip.

8. An ironing board comprising a body in the 45 form of an envelope embracing spaced top and bottom surfaces and edge walls, said envelope being open at one end, an electric heater disposed within said envelope adjacent such open end, a switch for controlling said heater and also disposed adjacent said open end, said top surface being formed with perforations and a closure strip for sealing the open end of said envelope against the escape of liquid from the interior of the same.

9. An ironing board comprising a hollow body, the top surface of said body being formed with 50 perforations and an electric heater disposed within said body solely adjacent its end, said heater comprising at least two spaced electrodes between which current may flow through liquid within said body to vaporize parts of said liquid for discharge through said perforations with minimum heating of the entire liquid content.

10. An ironing board comprising a hollow body, the top surface of said body being formed with 55 perforations and an electric heater disposed within said body solely adjacent its end, said heater comprising at least two spaced electrodes between which current may flow through liquid within said body to vaporize parts of said liquid for discharge through said perforations with minimum heating of the entire liquid content.

11. An ironing board comprising a hollow, elongated body presenting upper and lower surfaces, the upper surface of said board being formed with perforations for the passage of vapor, a partition extending centrally within said body from a point adjacent one end of the same to a point short of the opposite end to thus furnish a chamber between such latter end and the end of the partition, said chamber being common to the spaces within said body to either side of said partition and liquid vaporizing means disposed solely within said chamber.
